UNITED STATES PATENT OFFICE.

FRED L. STONE, OF SCHENECTADY, NEW YORK, ASSIGNOR TO GENERAL ELECTRIC COMPANY, A CORPORATION OF NEW YORK.

ELECTRICALLY-OPERATED HOIST.

1,200,264.

Specification of Letters Patent.

Patented Oct. 3, 1916.

Application filed September 14, 1914. Serial No. 861,504.

To all whom it may concern:

Be it known that I, FRED L. STONE, a subject of the King of Great Britain, residing at Schenectady, county of Schenectady, State of New York, have invented certain new and useful Improvements in Electrically-Operated Hoists, of which the following is a specification.

My invention relates to electrically operated hoists and has for its object the provision of means whereby the overwinding of the hoist due to carelessness of the operator or other cause is prevented.

In the operation of hoisting machines, such, for instance, as mining hoists, the cages travel at a relatively high speed, and it is therefore necessary that the motor be slowed down some time before the stopping point is reached in order to effect a safe landing without over travel. For instance, if the operator should neglect to slow down his motor when the cage nears the limit of its upward travel it may be impossible to stop it at the landing and it will therefore overtravel and may cause serious damage.

One of the objects of my invention is to provide means whereby in case the operator fails to slow down at the proper time or at the proper point in the operation of the hoist the motor circuit will be automatically opened.

In carrying out my invention I provide two circuit controlling devices for controlling the motor, one controlled by the speed of the motor and the other controlled by the position of the hoist. The arrangement is such that the motor circuit can only be closed when the circuit controlling devices are in corresponding positions, that is, when the hoist is in a certain position, the motor must be at a certain speed, otherwise the motor circuit will be opened. In this way, when the cage reaches certain positions at which the operator should slow down to a certain speed, if he does not slow down to this speed the motor circuit will be opened, and the hoist will be automatically stopped.

Other objects and features of my invention will appear in the course of the following specification in which I have disclosed my invention embodied in concrete form for purposes of illustration.

The accompanying drawing illustrates my invention applied to one form of electrically driven hoist.

Referring to the drawing, it will be seen that I have shown my invention in connection with what is known as a balanced hoist, in which there are two cages moving in opposite directions. It is obvious, however, that my invention is in no sense limited in its application to this particular form of hoist. The two cages are indicated at C, C' attached to two cables c, c'. These cables wind and unwind from the drums D and D', which are mounted upon the shaft S driven by an electric motor M, which is here illustrated as a three phase induction motor. Current is supplied to the motor by the three legs 1, 2, 3 of a three phase supply line, controlled by a switch 4, here represented as one which can be opened and closed by an electromagnet 5 in a control circuit 6 supplied with current from mains 7. The rotor of the motor is equipped with collector rings 8 connected to a resistor through switches in a receptacle 9 connected to a controller 10, so that the operator can slow down the motor at the end of the run by cutting resistance into the rotor circuit. A brake disk 11 on the shaft cooperates with a brake shoe 12, which is withdrawn from the disk by a coil 13 in the control circuit 6 when control circuit is closed. A speed responsive device 14, here represented as a flyball governor, is geared to the shaft, and actuates the movable contact of a switch, preferably by means of a lever 15 fulcrumed at 16, and having one arm pivotally engaged with the movable sleeve 17 of the speed governor. The other end of the lever is connected to two sliding contacts 18, 19, each co-operating with its own set of insulated segments 20, 21 and also with a single contact 22, 23, parallel with said segments. The movable contacts 18, 19 are mechanically, but not electrically, connected, preferably by the rigid rod 24 on which they are mounted, but from which they are insulated. The contacts 22, 23, form part of the control circuit 6.

The shaft S carries two pinions which mesh with spur gears 25, 26 secured to two long screws 27, 28, the former right hand and the latter left hand. Engaged with each screw is a fleeting nut 29, 30, restrained from rotation by guide rods 31, along which they can slide. Parallel with the screws are the rods 32, 33, each attached to an insulated contact 34, 35 which co-operates with

a bank of insulated segments 36, 37. The two contacts 34, 35 are electrically connected, for example, by the flexible conductor 38, and are long enough to cover all the segments in their respective banks. The rods 32, 33 are in line with the nuts 29, 30 respectively, so that they will be struck by said nuts when the latter travel to the left in the drawing. A weight 39 attached to a cord 40 connected to each contact 34, 35 and running over a pulley 41, brings the contacts back to the right when the nuts are backed away.

The segments in all four banks 20, 21, 15 36, 37 are equal in number, and those in banks 20, 21, numbering from left to right, are connected electrically by groups of conductors 42, 43 respectively, with corresponding segments in banks 36, 37, numbering 20 from right to left; the two groups of conductors and their terminal segments forming portions of the control circuit, connected in series.

The operation is as follows: Assume the 25 parts to stand as in the drawing, and that the engineer starts to hoist the cage C. The motor acquires full speed very quickly and maintains a uniform speed until near the end of the run, when the operator is supposed to cut the resistance into the rotor circuit and slow it down to bring the cage safely and accurately to the landing, where it is stopped by opening the motor circuit and applying the brake. As the motor acquires full speed, the governor balls will move out to the dotted position, and the contacts 18, 19 will be pulled over to the left hand segments of the banks 20, 21. At the same time the nut 29 is rapidly withdrawn by the screw 27, allowing the bar contact 34 to slide over the segments 36 at the same rate that the contacts 18, 19 are drawn over the segments 20, 21, thus keeping the control circuit 6 closed. If the engineer cuts in his motor too rapidly, the speed controlled contacts 18, 19 will outrun the cage controlled contact 34 and the motor circuit will be opened at the switch 4. Assuming, however, that this has not occurred, the cage will be hoisted rapidly until, near the end of its run, the engineer begins to cut in resistance to slow down the motor. Just here the nut 30, which has been traveling along its screw as the cage came up, 55 strikes the rod 33 and begins to push back the bar contact 35. Simultaneously, the speed governor, slowing down with the motor, begins to push the contacts 18, 19 to the right over the segments 20, 21 at the same speed as the contact 35, until, when the cage C comes to the top, the speed controlled switch will be in the position illustrated, and the contacts 34, 35 will occupy positions the reverse of those shown. If the engineer 60 does not slow down the motor soon enough,

but permits the speed governor to hold the contacts 18, 19 at the left until after the nut 30 has begun sliding the contact 35 to the left over the segments 37, the control circuit will be broken at one of these segments and 70 the motor will be stopped. So, too, if the engineer does not stop the cage when the contact 35 is on the last of the live segments 37, the contact will run off on the dead segment, break the control circuit, and 75 stop the cage.

The drawing is wholly illustrative and does not attempt to show the parts in their proper proportions or relations. The screws 27, 28 will have to be of a steep pitch in 80 order to shift the contacts 34, 35 over the entire bank of segments 36, 37 during the comparatively short time in which the motor is accelerating and slowing down. In other words, the fleeting nuts will be traveling 85 idly for the greater part of the length of said screws, coming into service only at the outer ends of the screws. If necessary, the movement of the nuts could be multiplied by suitable means to insure a greater and 90 quicker travel of the contacts 34, 35, as will be readily apparent to the skilled engineer. It is also evident that if the system is applied to a hoist having but one cage, the switches 21 and 35 and the group of circuits 95 43 could be dispensed with; the bar 23 being connected directly to the contact 34.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other 105 means.

What I claim as new and desire to secure by Letters Patent of the United States, is:—

1. The combination with the motor of an electric hoist, of means for gradually varying the speed of said motor between certain points in the travel of the hoist, comprising a controller, a speed responsive device actuating the same to various positions, a second controller actuated by the hoist, and connections between the controllers for effecting the control when the controllers are not in corresponding positions.

2. The combination with the motor of an electric hoist, of means for automatically 110 controlling said motor comprising two circuit controlling devices connected in series in the motor control circuit and adapted during acceleration and deceleration of the hoist to assume corresponding positions, one 115 controlled by the speed of the motor and the other controlled by the position of the cage or number of revolutions of motor.

3. The combination with the motor of an electric hoist, of means for automatically 120

- controlling said motor comprising two circuit controlling devices each having a plurality of controlling positions, one of said devices being controlled by the speed of the 5 motor and the other controlled by the position of the cage or number of revolutions of motor, and connections whereby the two devices must be in corresponding positions in order that the motor circuit will be closed.
- 10 4. The combination with the motor of an electric hoist, of a control circuit therefor containing a group of parallel conductors, a switch at one end of said group controlled by a speed responsive device, and a switch at the other end of said group controlled by the movement of the cage.
- 15 5. The combination with the motor of an electric hoist having two oppositely moving cages, of a control circuit therefor containing two groups of parallel conductors said groups being connected in series, switches at the remote ends of said groups controlled simultaneously by a speed responsive device, and electrically connected switches at the adjacent ends of said groups controlled respectively by the cage driving mechanisms.
- 20 6. Means for preventing the overwinding of an electric hoist, comprising an electric control circuit for the motor, a plurality of 25 circuits each terminating at each end in the corresponding segment of a bank of segments, a speed controlled switch connected to the control circuit and coöperating with one bank of segments, and a switch coöperating with the other bank and actuated by the hoist during the latter part of its travel.
- 25 7. Means for preventing the overwinding of an electric hoist driving two winding drums, comprising an electric control circuit 30 for the motor which includes two groups of parallel conductors each terminating at each end in one of a bank of segments, two switches coöperating with the segments at one end of said groups, a speed responsive device operatively connected to both switches, connected switches coöperating with the segments at 35 the other end of said groups, and mechanism geared to each cage for operating its respective switch during the upper portion of its travel only, both in hoisting and lowering, and simultaneously with the movement of the speed controlled switches.
- 40 8. Means for preventing the overwinding of an electric hoist driving two cages, comprising an electric control circuit for the motor which includes two groups of parallel conductors each terminating at each end in one of a bank of segments, two switches coöperating with the segments at one end of said groups, a speed responsive device operatively connected to both switches, connected switches coöperating with the segments at the other end of said groups, and mechanism geared to each cage for operating its respective switch during the upper portion of its travel only, both in hoisting and lowering, and simultaneously with the movement of the speed controlled switches.

device operatively connected to both 45 switches, electrically connected switches coöperating with the segments at the other end of said groups, and mechanism geared to each drum for operating its respective switch.

50 8. Means for preventing the overwinding of an electric hoist driving two cages, comprising an electric control circuit for the motor which includes two groups of parallel conductors each terminating at each end in one of a bank of segments, two switches coöperating with the segments at one end of said groups, a speed responsive device operatively connected to both switches, connected switches coöperating with the segments at the other end of said groups, and mechanism geared to each cage for operating its respective switch during the upper portion of its travel only, both in hoisting and lowering.

65 9. Means for preventing the overwinding of an electric hoist driving two cages, comprising an electric control circuit for the motor including two groups of parallel conductors each terminating at each end in one 70 of a bank of segments, two switches coöperating with the segments at one end of said groups, a speed responsive device operatively connected to both switches, connected switches coöperating with the segments at 75 the other end of said groups, and mechanism geared to each cage for operating its respective switch during the upper portion of its travel only, both in hoisting and lowering, and simultaneously with the movement of the speed controlled switches.

In witness whereof, I have hereunto set my hand this 12th day of September, 1914.

FRED L. STONE.
